MACHINE FOR BINDING BOOKS

Sidney M. Penner, Bronx, N. Y., assignor, by
mesne assignments, to Rudolf Tauber, Brook-
lyn, N. Y.

Application October 23, 1948, Serial No. 56,143

2 Claims.

(Cl. 11—1)

1

This invention relates to a book binding machine, especially adapted for use in the spiral book binding industry.

Presently known machines used for the spiral binding of books have proved to be unsatisfactory when plastic bindings were desired. Wire bindings possess an inherent rigidity which enables them to be driven through the perforations in a sheaf of papers, despite irregularities in the register of the said perforations. Plastic binding, however, tends to wander out of the holes because of the extreme flexibility of the material.

It has thus been found necessary to orient the perforations in the sheaf so that the path therethrough corresponds to the portion of the spiral binding which will pass through it. The sheaf of pages must then be held in this position until the binding operation is completed.

Another difficulty which has been encountered in using plastic bindings is the tendency of the plastic to wander out of its spiral path as it is being driven through the book. This characteristic of plastic bindings is amplified if the means used for driving the plastic through the perforations deforms the said binder.

Accordingly, the object of this invention is to provide a binding machine and a method which will overcome the above and other objections, and perform successfully when plastic bindings are desired.

Another object of this invention is to provide an inexpensive binding machine capable of handling a wide variety of binding sizes.

A further object of this invention is to increase the rate of spiral binding by decreasing the number of operations required.

A feature of this invention is its novel pilot bar construction for guiding the plastic bindings.

A further feature of this invention is the provision of retractable hooks to orient the binding perforations.

A feature of this invention is the clamping means for holding the sheaf until bound.

A further feature of this invention is the construction of the guiding comb for maintaining the path of the binding material.

The invention consists of the construction, combination and arrangement of parts, as hereinafter illustrated, described and claimed.

The accompanying drawings, forming a part hereof, illustrate one form of embodiment of the invention, in which drawings similar reference characters designate corresponding parts, and in which:

Figure 1 is a front elevational view of a binding machine according to this invention.

Figure 2 is a view in side elevation of the binding machine, according to this invention, with the clamping means shown in a somewhat elevated position for the purpose of clarifying the drawing.

Figure 3 is a view in perspective, somewhat enlarged, of the hook retracting mechanism of the binder with several parts shown in dashed lines for the sake of clarity.

Figure 4 is a fragmentary view somewhat enlarged, showing the binding drive mechanism, according to this invention.

Figure 5 is a sectional view taken on line 5—5 of Figure 4.

Figure 6 is a fragmentary top plan view, somewhat enlarged, of the pilot bar construction.

Figure 7 is a fragmentary view, somewhat enlarged, of the hook mechanism, according to this invention.

Figure 8 is a fragmentary view on the scale shown in Figure 7, showing the hook mechanism in the retracted position.

Figure 9 is a fragmentary vertical section somewhat enlarged, taken on line 9—9 of Figure 2.

Figure 10 is a fragmentary view in front elevation of a bound book, according to this invention.

Referring to the drawings, and particularly to Figure 1, 11 indicates a support table to the top of which are secured two spaced upright members 12, 13, forming a frame for the machine. A rotatable bar 14 is carried at each end thereof by the upright members 12, 13 at a point spaced from the top of the said upright members 12, 13.

The bar 14 supports a clamping device 15, hereinafter more fully described. The left hand end of the bar 14 carries a crank arm 16 attached thereto. This arm 16 serves to prevent the longitudinal movement of the bar 14 and also operates, in conjunction with a spring 17, to maintain the clamping device in either the opened or closed position. The position of the arm 16 upon the bar 14 is such that when the clamping device 15 is brought down the arm 16 moves past the vertical position and the coil spring 17 is enabled to pull it down, thereby tightening the hold of the clamping device 15. When the clamping device 15 is raised, it rotates the arm 16 to a point past the vertical in the opposite direction,

causing the spring 17 to hold the said clamping device in an open position. The pressure of the clamping device 15 is further increased when in the closed position by a linkage 18 secured to the right hand end of the bar 14. Said linkage 18 is

hereinafter more fully described in connection with the operating mechanism.

A pivot bar 19 is carried intermediate the two upright members 12, 13 and below the bar 14. The pivot bar 19 is journaled within the members 12, 13 and extends therebeyond a short distance. The right hand end 20 of the said bar 19 has a greater extension beyond the frame of the machine than the left hand end of the said bar.

Two flat blocks 21, 22 are secured to the pivot bar 19 and spaced from each other so that they are adjacent the inner faces of the upright members 12, 13. These blocks 21, 22 are secured to and free to rotate with the pivot bar 19 within limits set by stops 23 and 56.

The blocks 21, 22 carry a shaft 25 which in turn has a resilient roller 26 secured thereto. The roller shaft 25 is spaced from the top of the blocks and toward the front thereof. One end of the roller shaft 25 extends beyond the left hand block 21, and is provided with a pulley 27 or other suitable means for receiving rotary power from a motor 28.

A hook bar 24 is also carried by the blocks 21, 22 at a point below the roller shaft. This bar 24, best shown in Figure 3, is offset from its terminal shafts 29, 30 so as to impart a larger ambit of rotation to the hooks 31, 32 carried by the said bar 24. Each of the shafts 29, 30 is freely turnable within its respective block 21, 22. The right hand shaft 30, however, is threaded and engages a nut 33 which is secured to the outside of the block 21. Thus, as the hook bar 24 is rotated, it is also caused to move axially by its threaded engagement with the nut 33.

The hooks 31, 32 on the hook bar 24 extend from the front face of the said bar 24 and enter openings in a stationary comb member 36. The comb member 36 is set into the upper part of the face of a work-table 37 (see Figure 4) and its work face is flush therewith. The work table 37 is inclined at a suitable angle, as shown in Figure 2, and is mounted upon the support table 11.

The comb member 36, best shown in Figures 4, 5, 7 and 8, consists of a plate 38 having a plurality of notches 39 cut into the upper edge thereof. All of the notches 39 are skewed to conform to the pitch of the spiral binder to be used, and are formed to span the holes 41 in the book 42. Each notch 39 provides a path through which the binding material 40 can pass in traveling through the perforations 41 in the book 42. Immediately behind the plate 38 there is located a guide plate 43. This plate 43 may be made of plastic or some other suitable material. The function of the guide plate 43 is to prevent the binder 40 from wandering out of the comb 36 while it is being driven through the book 42.

The comb member 36 has its counterpart on the clamping device 15 previously referred to in connection with Figures 1 and 2. This clamping device 15 comprises two arms 44 secured to the hold-down bar 14, as by screws 45. The arms 44 are spaced from each other and support a plate 46. A second plate 47 is carried by the first plate 46 on two studs 48. These studs 48 are secured to the back of the plate 47 and extend through holes 49 in the plate 46. The two plates 46, 47 are maintained in a yieldably spaced relationship with each other by reason of coil springs 50 between the plates 46, 47 and two nuts 51 which are secured to the extended ends of the studs 48. The comb 52, attached to the front plate 47 is identical in construction with

that previously described upon the work table. Thus, when the hold-down bar 14 is rotated and the clamping device 15 brought down, the book 42 to be bound is grasped between the combs 36, 52, and held in place until the binder 40 is driven therethrough.

The driving operation is performed through the cooperation of the roller 26 mounted upon the shaft 25 and a pilot bar 53. The said pilot bar, shown in Figures 1, 4 and 6, is secured to the table 37 by two studs 54. These studs 54 engage the bar 53 at a point between the convolutions of a helical groove 55 cut into the bar 53. The groove 55 has the same pitch as that required for the binder 40 to pass through the perforations 41 of the book 42. However, the depth of the groove 55 is only equal to one half the diameter of the binder 40 (see Figures 5 and 6). Thus, as the roller 26 is brought down upon the binder 40 and rotated by the motor 28, the said binder 40 is caused to rotate and travel across the pilot bar 53 in the direction of the book 42.

Since the roller 26 is as long as the pilot bar 53 the binder 40 will continue to be driven forward until its end leaves the said bar. By using lengths of binder equal to the required binding of the book, the binding operation can be stopped automatically as the binding spiral 40 leaves the pilot bar 53. This feature eliminates the need for cut-off or limit switches which have been necessary with other machines.

Referring again to Figures 1, 2 and 3, it will be seen that as the lever 35 leading to the treadle 33 is depressed, it will turn the shaft 30. The shaft 30 will thus cause the hook bar 24 to move from the position shown in Figure 7 to that of Figure 8. The hooks 31, 32 will then be withdrawn from the holes 41 in the book 42. At the same time, by reason of the fact that the pitch of the thread on the shaft 30 is the same as that of the spiral binder 40, the hook bar 24 will be moved slightly to the right, thereby effecting a clean withdrawal of the hooks 31, 32, without disturbing the alignment of the pages of the book 42.

As the downward motion of the lever 35 is continued, the rotation of the shaft 30 will be halted by a stop member 56. This stop member 56 is provided with two arms 57, 58 at right angles to each other. The lower arm 58 moves up as the treadle is pushed down until it strikes the end of the pivot bar 19. As the downward motion of the treadle is continued the blocks 21, 22 are caused to rotate upon the pivot bar 19 against the pull of the spring 59 until the stop 23 is reached. The stop 23 is adjusted so that the roller 26 will engage the binder 40 with the proper amount of pressure when the blocks 21, 22, which carry the roller shaft, strike the said stop.

Referring to Figures 1, 2, 3 and 9, it will be seen that an arm 60 is secured to the shaft 30 intermediate the stop 56 and the nut 33. This arm 60 carries a pin 61 through which is secured a rod 62. The upper end of the rod 62 passes through a second pin 63 and is slidably held thereby. A coil spring 64 is slipped over the extended end of the rod 62 so that its lower end bears against the pin 63 and its upper end against a stop 65 carried by the rod 62. The upper pin 63 is pivotally carried by the linkage arm 18 previously mentioned herein. Thus, as the shaft 30 is rotated, the rod 62 is drawn down, causing the spring 64 to yieldably force

the hold-down clamping device 15 against the book 42.

The operation of the binding machine can be followed from the foregoing description. The motor 28 is started. With the hooks 31, 32 in the extended position shown in Figure 7, the operator places a sheaf of pages to be bound so that the holes thereof are engaged thereon. A length of binding material such as a helical plastic strip 40 is next slipped upon the pilot bar and given a slight start in the groove 55. The clamping device 15 is then brought down manually, or by some suitable linkage associated with the treadle, until it bears against the top of the book 42. The spring 17 and the arm 16 co-operate to hold the book 42 between the two combs 36, 52.

The foot treadle is then depressed, causing the hook bar 24 to rotate and withdraw the hooks 31-32 from the holes 41 of the book 42. This action also tightens the hold of the clamping device 15, as previously described. As the treadle is carried down further, the blocks 21, 22 are caused to rotate, thereby bringing the revolving roller 26 into contact with the top of the binder 40, as shown in Figures 4 and 5. The roller 26 spins the binder 40 through the groove 55 in the pilot bar 53, thereby causing the said binder 40 to twist its way between the comb members 36, 52, and consequently through the holes 41 of the book 42.

When all of the binder 40 has left the pilot bar 53, the book will be bound, as shown in Figure 10. The treadle is then released. This operation removes the roller 26 from its position above the pilot bar 53, while at the same time allowing the coil spring 64 to expand, loosening the hold of the clamping device 15. The bound book can thus drop into a chute or receptacle (not shown). As the treadle is brought back into the original position by the springs 66, the hook bar 24 rotates until the upper arm 58 of the stop 56 strikes the extended end of the pivot bar 19. The machine is then back in its original position, with the hooks projecting through the teeth of the fixed comb member 36 ready to have another book placed thereon.

It is clear that the size of the bindings may be varied by changing the size of the pilot bar.

The retractable hooks 31, 32 not only serve to engage the book to be bound, but act to orient the perforations therein, so that they offer a minimum of resistance to the helical passage of the binder therethrough. The removal of the hooks 31, 32 during the actual binding operation also provides the maximum space for the passage of the binder 40 through the holes 41.

Having thus fully described the invention, what is claimed as new and desired to be secured by Letters Patent of the United States, is:

1. A machine for spirally binding a sheaf of papers into a book comprising, a base, an inclined work table on the said base, a lower clamp jaw carried upon the work table, an upper clamp jaw secured to an arm swingably mounted upon the base so as to permit the jaws to be brought together to hold the sheaf of papers, said sheaf having a series of perforations therein along the edges to be bound, a comb member upon the edge of each jaw adapted to support the sheaf adjacent the perforations, a plate carried on the outside of each comb member and parallel therewith to confine the travel of the binding material, hooks swingably carried by the base intermediate the comb teeth of the lower clamp jaw and projecting above the surface of the work table, said hooks being retractable so as to remove them from the jaws after the sheaf has been grasped by the jaws, said hooks having a curvature and inclination suitable for alining the perforations in the sheaf to correspond with the path of a spirally shaped binding material and means movably mounted upon the base adjacent the lower clamp jaw to drive a binding material through the aligned perforations in the sheaf.

2. A machine for spirally binding a sheaf of papers into a book comprising, a base, an inclined work table on the said base, a lower clamp jaw carried upon the work table, an upper clamp jaw secured to an arm swingably mounted upon the base so as to permit the jaws to be brought together to hold the sheaf of papers, said sheaf having a series of perforations therein along the edges to be bound, a comb member upon the edge of each jaw adapted to support the sheaf adjacent the perforations, a plate on the outside of each comb member and parallel therewith, hooks swingably carried by the base intermediate the comb teeth of the lower clamp jaw and projecting above the surface of the work table, said hooks being retractable so as to remove them from the jaws after the sheaf has been grasped by the jaws, said hooks having a curvature and inclination suitable for aligning the perforations in the sheaf to correspond with the path of a spirally shaped binding material and means including a helically grooved pilot bar and a driven roller movably mounted upon the base adjacent the lower clamp jaw to drive a binding material through the aligned perforations in the sheaf.

SIDNEY M. PENNER.
